UNITED STATES PATENT OFFICE

1,939,549

RADIANT GAS HEATER

Robley B. Gulley, Smackover, Ark.

Application July 30, 1932. Serial No. 626,954

5 Claims. (Cl. 126—92)

This invention relates to a radiant gas heater and it aims to provide a relatively simple and inexpensive construction which will radiate maximum heat.

6 Another object is to provide a construction which will have a down draft and further has novel means whereby the combustible mixture is discharged within the radiants and wherein the radiants are detachably mounted in a novel 10 manner.

The more specific objects and advantages will become apparent from a consideration of the description following taken in connection with accompanying drawings illustrating an operative 15 embodiment.

In said drawings:—

Figure 1 is a view in elevation of the improved heater,

20 Figure 2 is a cross sectional view taken on the line 2—2 of Figure 1,

Figure 3 is a cross sectional view taken on the line 3—3 of Figure 1,

25 Figure 4 is an enlarged central longitudinal section taken on the line 4—4 of Figure 1, and

Figure 5 is an enlarged detail on the same plane as Figure 4 through the lower portion of one of the radiants and the adjacent structure.

Referring specifically to the drawings, 10 designates a casing supported by legs at 11 and perforated as at 12 for the entrance of the air necessary to combustion. The cover for the casing is shown at 13 and connected thereto is a suitable 15 guard structure or railing 14.

Secured centrally to the cover 13 by nuts 15 is 20 a metallic rod 16 which detachably mounts a frusto-conical body 17 of metal, fire clay or any other desired material, the same being disposed on the rod in inverted position and being cut away as at 18 to accommodate the adjacent nut 15. At the top, the body 17 is cut away as at 19 to accommodate a nut 20 screw-threaded on the rod and aiding in clamping the body 17 in place.

Arranged about the body 17 so as to completely 25 cover the periphery thereof, are a plurality of removable radiants 21 of segmental shape as best shown in Figure 1. These radiants may be of any suitable material. For instance, they have backings of metal 22 and facings 23 of clay or a combination thereof, and asbestos. As best shown 30 in Figure 5, the lower portions of the backings have combustion passages 24 therein in communication with the atmosphere through burner orifices 25. The cover 13 has an annular groove or depression 26 about the body 17 and a flange or 35 wall 27 rises therein having orifices 28 there-

through in line with the burner orifices 25. The radiants extend removably into such groove 26.

At the top the radiants are held in place by a plate 29 through which rod 16 extends, and which plate has a depending flange at 30 engaging the upper end portion of the radiants. A nut or spacing sleeve 31 is screw-threaded to the rod 16 above the plate 29 to secure the latter in place and the rod also passes through a canopy or hood 32 which rests on the sleeve 31 and is secured in place by an ornamental nut 33 threaded to a reduced portion 34 of the hood. It will be noted that the hood adjacent the upper portion thereof has gas outlets at 35, and that the hood may be of any desired size, that shown being adapted to direct the heat relatively low and about the floor.

Within the casing 10 a fuel tank or reservoir 36 is suitably supported as at 37 and a gas supply pipe 38 leads thereto. A multiplicity of burner pipes 39 extend from the reservoir through the 75 base wall at groove 26 and communicate with the spaces 24 to supply fuel thereto. Such fuel passing through the burner pipes 39, however, is admixed with air taken in through the ports 12, through the adjustment and operation of 80 air admission devices 40 of a conventional type and hence unnecessary to specifically describe.

It will also be noted that the wall 41 of the cover opposite the burner orifices 24—28, is perforated as at 42, so that further air desired for 85 combustion may be taken up by the fuel mixture.

Various changes may be resorted to provided they fall within the spirit and scope of the invention.

What is claimed is:—

1. A stove of the class described having a casing, an upstanding body thereon, radiants surrounding said body disposed at an upwardly and outwardly extending angle having combustion passages and orifices adjacent the lower ends of 95 the passages leading therefrom to the atmosphere, a fuel reservoir within the casing, and burner pipe means leading from the reservoir to said passages.

2. A stove of the class described having a casing, an upstanding body thereon, radiants surrounding said body disposed at an upwardly and outwardly extending angle having combustion passages and orifices adjacent the lower ends of 100 the passages leading therefrom to the atmosphere, a fuel reservoir within the casing, burner pipe means leading from the reservoir to said passages, said casing being perforated whereby 105 it is open to the atmosphere, said casing about said body having a groove, said radiants being 110

removable and having their lower ends disposed in the groove, said radiants also having orifices communicating with said passages and said groove and means above said ends securing the 5 radiants in place.

3. A stove of the class described having a casing, an upstanding body thereon, radiants surrounding said body disposed at an upwardly and outwardly extending angle having combustion 10 passages and orifices adjacent the lower ends of the passages leading therefrom to the atmosphere, a fuel reservoir within the casing, burner pipe means rising from the reservoir to said passages, said casing being perforated whereby it 15 is open to the atmosphere, said casing about said body having a groove, said radiants being removable and having their lower ends disposed in the grooves, a plate at the top of the body securing said radiants to the body, and a rod rising 20 from the casing mounting said body and plate.

4. A stove of the class described having a casing, an upstanding body thereon, radiants surrounding said body having combustion passages and orifices adjacent the lower ends of the 25 passages, a fuel reservoir within the casing, burner pipe means leading from the reservoir to said

passages, said casing having perforations whereby it is open to the atmosphere, said casing about said body having a groove with which the orifices communicate, said radiants being removable and having their lower ends disposed in the groove, a rod rising from the casing on which said body is mounted, a hood carried by the rod about said body having gas outlets therein, a plate on said rod having a flange engaging the upper end of said radiants, and a spacing member on the rod above the plate from which said hood is suspended.

5. A heater of the class described having a casing provided with a groove, radiants having their lower ends disposed in said groove, said radiants having passages therein and orifices leading therefrom to the atmosphere, a wall in said groove engaging the outer surfaces of the radiants and having orifices registering with said first mentioned orifices, the casing having a wall outwardly of said first mentioned wall and spaced from the latter wall at the top and provided with air outlet openings adjacent said second mentioned orifices.
